Primary Examiner — Dana L Meyrow*(74) Attorney, Agent, or Firm* — James E. Oehlenschlager**CLAIM**

The ornamental design for a bottle with label, as shown and described.

DESCRIPTION

FIG. 1 is a front perspective view of a bottle with label showing our new design;
 FIG. 2 is a front elevation view thereof;
 FIG. 3 is a left side elevation view thereof;
 FIG. 4 is a right side elevation view thereof;
 FIG. 5 is a rear elevation view thereof;
 FIG. 6 is a top plan view thereof;
 FIG. 7 is a bottom plan view thereof;
 FIG. 8 is a front perspective view of a second embodiment of a bottle with label showing our new design;
 FIG. 9 is a front elevation view thereof;
 FIG. 10 is a left side elevation view thereof;
 FIG. 11 is a right side elevation view thereof;
 FIG. 12 is a rear elevation view thereof;
 FIG. 13 is a top plan view thereof; and,
 FIG. 14 is a bottom plan view thereof.

The broken lines in the drawings illustrate the portions of the bottle with label that form no part of the claim.

1 Claim, 10 Drawing Sheets(56)
